UNITED STATES PATENT OFFICE.

FRANK C. DE REAMER, OF SCHENECTADY, NEW YORK, ASSIGNOR TO GENERAL ELECTRIC COMPANY, A CORPORATION OF NEW YORK.

ATTACHMENT-PLUG.

1,115,654.

Specification of Letters Patent.

Patented Nov. 3, 1914.

Application filed April 15, 1913. Serial No. 761,208.

To all whom it may concern:

Be it known that I, FRANK C. DE REAMER, a citizen of the United States, residing at Schenectady, county of Schenectady, State 5 of New York, have invented certain new and useful Improvements in Attachment-Plugs, of which the following is a specification.

My invention relates to connectors for 10 electric conductors, and more particularly to attachment plugs designed for connecting the feed wires of small electrical apparatus, such as fan motors, heaters, portable lamps, etc., to a service circuit by the mere insertion 15 of the plug into a socket or receptacle such as is commonly used for the ordinary incandescent lamp.

The object of my invention is to provide a durable, simple, cheap and compact device 20 of this character.

In carrying out my invention, I provide a socket plug member and a separable wire engaging member. I provide each of these members with contacts or contact clips 25 adapted to engage those of the other, and I also provide the socket plug member with means for making connection between its clips and the contact means of the lamp socket, such as a center contact and a contact 30 shell to one of which each clip is electrically connected. In the construction of the socket plug member, I arrange within the contact shell an insulating base part or member having in it openings for the contact clips, and 35 I employ an insulating disk part or member that separates the shell and center contacts and helps in securing these contacts and the contact clips in the proper relative positions. Rapid assembling of the parts of the plug 40 member in the factory can be facilitated by securing some of them to the insulating disk independently of the insulating base before it and the insulating base are put together. This and other advantages are best realized 45 when disk, shell, center contact, and contact clips all form a unitary structure with the clips seated or mounted along with the shell and within the same on the opposite side of the disk from the center contact.

50 For a fuller understanding of my invention, reference may be had to the accompanying drawing, in which—

Figure 1 is a side elevation of the cap member; Fig. 2 is a longitudinal section of 55 the plug member embodying my invention; Fig. 3 is a longitudinal section of the insu-

lating base which forms a part of the attachment plug; Fig. 4 is a side elevation, partially in section, of the current carrying part of the plug member; and Fig. 5 is a 60 plan corresponding to Fig. 4.

In describing the parts of the attachment plug in Fig. 2, I shall, for convenience, describe them in the relations there shown, although it will, of course, be understood 65 that, in practice, the plug will be used in any position.

Referring to the drawing, and first to Figs. 2, 4 and 5, 1 is a clamping sleeve provided at its lower end with a flange 2 and 70 preferably formed immediately above the flange with a conical portion 3. A substantially disk-shaped insulating member 4 is seated upon the flange 2 and is provided with a central opening to receive the sleeve 1 75 and with shallow recesses 5 on the upper side thereof for a purpose hereafter explained. A screw-threaded contact shell 6, closed at the bottom by a transverse portion 7, is seated upon the member 4 and is provided 80 with a large central opening through which the sleeve 1 extends out of contact therewith. The transverse portion 7 is provided with downwardly extending protuberances 8 which engage the openings 5 of the insulating member 4 and prevent relative motion between the shell and the insulating member. This transverse portion 7 is also provided with upwardly extending protuberances 9 (see Fig. 5) for a purpose here 85 inafter explained. A contact clip 10 comprising an upwardly extending contact finger reversely curved or bent has at its lower end a transverse arm 11 which is seated upon the bottom portion 7 of the shell 6 and is provided with an opening registering with, but larger than, the base opening. A second contact clip 12, the finger portion of which is disposed opposite to contact 10, is also provided with a transverse arm 13 having 90 an opening to closely receive the sleeve 1. The contact clips 10 and 12 are separated by an insulating disk 14 disposed between the transverse arms 11 and 13 of the clips and having a contracted portion extending 95 through the opening of the transverse arm 11. The contact clip 10 is thus electrically connected to the shell 6 while the clip 12 is connected to sleeve 1. The members forming 100 the structure shown in Fig. 4 are held together by the clamping sleeve 1 which is provided at its upper end with a flange 16 105 110

which may be formed by a punch press in a well understood manner. I will, for convenience, hereafter refer to this structure as a connection unit.

- 5 An insulating base 17 is exteriorly divided by shoulders 18 and 19 into cylindrical sections of different diameters, the lower section being of such a diameter as to be received in the screw-threaded shell 6.
- 10 The base is interiorly provided with two longitudinally extending openings 20 which are adapted to receive the contact fingers 10 and 12. The insulating base is also provided with a central opening 21 for the reception of a member which secures the unit shown in Fig. 4 to the base. The bottom of the base is cored out centrally at 22, so that the bottom of the base may pass over the insulating disk 14, and the top of the 20 insulating base is cored out at 23. The bottom of the base is provided with recesses 24 (shown in dotted lines in Fig. 3), within which the upwardly extending protuberances 9 of the transverse portion 7 of the shell are received. A nut 25 is seated in the opening 23 and receives a screw 26, the head of which engages the conical portion 3 of the sleeve 1 and clamps the connection unit to the insulating base. The opening about the nut may be sealed by cement or otherwise.

The separable wire engaging member (see Fig. 1) comprises an insulating base 28 provided with projecting contact fingers 29 and 30 reversely bent or curved to the fingers 10 and 12, and with which they are adapted to engage and interlock. Conductors 31 are electrically connected to the contact fingers 29 and 30 and in turn lead to any suitable electrical apparatus.

A plug attachment made in accordance with my invention is easily assembled and is compact and shorter than the ordinary plug attachment, and it possesses the added 45 advantage that the loosening of the screw which clamps the connector to the insulating base does not affect the contacts.

In accordance with the provisions of the patent statutes, I have described the principle of operation of my invention, together with the apparatus which I now consider to represent the best embodiment thereof; but I desire to have it understood that the apparatus shown is only illustrative, and that 55 the invention can be carried out by other means within the scope of my claims.

What I claim as new and desire to secure by Letters Patent of the United States, is,—

- 60 1. A connection unit for an attachment plug comprising an insulating member and a contact shell extending upward therefrom, a center contact at the lower side of said insulating member, a pair of contact fingers in said shell having overlapping

portions adjacent said insulating member, another insulating member interposed between the overlapping portions of said fingers, and means secured to the first mentioned insulating member, extending 70 through the overlapping portions of said fingers and said latter insulating member and securing them to said first mentioned insulating member, one of said contact fingers being electrically connected to said contact shell and the other to said center contact.

2. A connection unit for an attachment plug comprising an insulating member provided with a central opening, an upwardly extending shell closed at one end seated upon said insulating member and having in its end closure an opening above the opening in said insulating member, a pair of contact clips having transversely disposed overlapping arms provided with openings above said opening in said insulating member, an insulating member interposed between the overlapping portions of said clips and a conductive clamping sleeve passing through the various openings and through said latter insulating members and secured at one end to said insulating member and at the other end to the upper one of the two clips.

3. In a connection unit for an attachment plug, a conductive sleeve provided at one end with a flange, an insulating member surrounding said sleeve and seated upon said flange, a contact shell closed at its lower end seated upon said insulating member, a pair of contact clips provided with transversely disposed overlapping arms and having openings to receive said sleeve, an insulating member interposed between the arms of said contact clips, one of said clips being electrically connected to said shell and the other to said sleeve, said sleeve being secured to the upper contact clip and the various members thus secured together.

4. In a connection unit for an attachment plug, a conductive sleeve provided at one end with a flange, an insulating member surrounding said sleeve and seated upon said flange, a contact shell closed at the lower end seated upon said insulating member and provided with protuberances which are received in corresponding recesses in the insulating member, a pair of contact clips each provided with transversely disposed arms and having openings to receive said sleeve, an insulating member located between the two contact clips, one of said clips being electrically connected to said shell and the other to said sleeve, said sleeve being secured to the upper contact clip and the various members thus secured together to form a unit.

5. In a connection unit for an attachment plug, an insulating member provided with a central opening, a screw-threaded metallic 130

- shell seated thereon and closed at one end and having an opening concentric with the opening in said insulating member, a pair of contact clips having transversely disposed 45 said openings secured against and electrically connected to said transverse portion of said contact shell also independently of said base.
5. In a separable electric connector, an insulating member, a center contact located 50 below the same and a contact shell closed at the lower end extending upwardly therefrom, the transverse portion of said shell being provided with upwardly and downwardly extending protuberances, a pair of 55 contact clips mounted within the shell, one of the clips being electrically connected to the center contact and the other to the contact shell, and an insulating base with its lower end in said contact shell having two 60 openings extending longitudinally thereof which accommodate said contact clips, the lower face of said insulating base and the upper face of the insulating member being provided with recesses in which the upwardly and the downwardly extending protuberances of the contact shell are respectively engaged.
6. In a separable electrical connector, the combination of an insulating member, a center contact below said member, and a contact shell extending upward from said member, an insulating base secured to said insulating member with its lower end in said contact shell, said base having two openings extending 65 longitudinally thereof, and contact clips in said openings secured to said insulating member independently of said base one of which is electrically connected to said center contact and the other to said contact shell.
7. In a separable electrical connector, the combination of a contact shell having a transverse bottom portion at its lower end, an insulating disk member below said contact shell, an insulating base in said contact shell having two openings extending longitudinally therethrough, said disk member and said base being secured together with said transverse portion of said shell between 70 them, a contact clip in one of said openings secured to said disk member independently of said base, a center contact below said disk member electrically connected to said contact clip, and a contact clip in the other of
8. In a separable electric connector, an insulating member, a center contact located 75 below the same and a contact shell closed at the lower end extending upwardly therefrom, the transverse portion of said shell being provided with upwardly and downwardly extending protuberances, a pair of 80 contact clips mounted within the shell, one of the clips being electrically connected to the center contact and the other to the contact shell, and an insulating base with its lower end in said contact shell having two openings extending longitudinally thereof which accommodate said contact clips, the lower face of said insulating base and the upper face of the insulating member being provided with recesses in which the upwardly and the downwardly extending protuberances of the contact shell are respectively engaged.
9. In an electric connector, the combination of an insulating member having a center contact at its lower side, an insulating base secured to said member having therein a pair of longitudinally extending openings, and a screw threaded contact shell and a pair of contact clips secured to said insulating member independently of said base and extending upwardly from said member around said base and within said openings in said base respectively, one of said contact clips being electrically connected to said contact shell and the other to said center contact.
- In witness whereof, I have hereunto set my hand this 14th day of April, 1913.
